UNITED STATES PATENT OFFICE.

RUSSELL H. WILHELM, OF EASTON, PENNSYLVANIA, ASSIGNOR TO INGERSOLL-RAND COMPANY, OF JERSEY CITY, NEW JERSEY, A CORPORATION OF NEW JERSEY.

PINNING-OUT MACHINE FOR DRILL-STEELS.

1,370,251.

Specification of Letters Patent.

Patented Mar. 1, 1921.

Application filed May 17, 1919. Serial No. 297,892.

To all whom it may concern:

Be it known that I, RUSSELL H. WILHELM, a citizen of the United States, residing at Easton, in the county of Northampton and 5 State of Pennsylvania, have invented a certain new and useful Improvement in Pinning-Out Machines for Drill-Steels, of which the following is a specification.

This invention relates to a pinning out 10 machine for drill steels.

The objects of the present invention are to provide a machine in which a drill steel may be securely clamped in position and a pin forcibly pushed into the central hole 15 with which this class of drill steel is provided, in order to clear the hole after the forging of either the bit or the lug end of the steel has been completed. Particularly, it is an object of the present invention to 20 control the elements forming this pinning out machine by means of a single valve which may be operated by a single conveniently mounted handle; movement of the handle in the forward direction first closing 25 the jaw members of the vise, a continued movement causing the pin to be pushed forwardly. A slight rearward movement of the handle from this extreme forward position, causes the pin to be pulled out of 30 the steel and a continued movement rearwardly of the handle causes the jaw members of the vise to open and release the drill steel.

A further object of the invention is to 35 convey the fluid exhausted from one of the cylinders to the point of the reciprocable pin to prevent the pin from becoming overheated.

With these and other objects in view my 40 invention consists in the features of construction and operation set forth in the following specification.

In the figures of the drawing annexed hereto:

Figure 1 shows a front end view of the complete pinning out tool, parts being shown in section at one side to more clearly illustrate the construction.

Fig. 2 a side view of the complete machine, parts being shown in section.

Figs. 3 to 8 show diagrammatically the position of the valve assumed when the handle is in its different operating positions.

Referring more particularly to the figures

of the drawing 1 refers to a pedestal or 55 standard upon which the pinning out machine may be conveniently mounted. A body member 2 is securely clamped in any suitable manner to the standard 1, this body member at its forward end mounting a vise 60 3 presently to be more fully described, and at its rear end a cylinder 4 forming a part of the mechanism for operating the reciprocable pin 5.

The vise shown at 3 comprises two oppositely positioned jaw members 6 and 7 which have a movement sufficient to allow the maximum size drill steel ordinarily used to be placed between them and securely grasped. The jaw members 6 and 7 are 70 operated to grasp the drill steel by means of a toggle mechanism comprising arms 8 and 9 adjoining and pivotally connected to the blocks in which the jaw members 6 and 7 are fitted by means of suitable pins 10 and 11. Pivoted about pins 14 and 15 located at either side of the machine in the body member 2 are arms 16 and 17. The upper ends of arms 16 and 17 join respectively the arms 9 and 8 and are attached 80 thereto by means of pins 18 and 19. The lower ends of the arms 16 and 17 are provided with suitable holes through which extend pins 20 and 21 to which arms 22 and 23 are attached. Arms 22 and 23 intercept 85 each other at their lower ends and are pivotally attached to a pin 25 secured in a cross head 26 at the upper end of piston rod 27. At the lower end of piston rod 27 is located a piston 28 operating within a cylinder 29, the piston rod 27 extending through a suitable stuffing box 29A. Cylinder 29 is supplied with motive fluid under pressure at points above and below the piston 28 by means of pipes 30 and 31, air being admitted to these pipes in accordance 90 with movement of a valve 32, the movement of which will be more clearly described later. With the piston in its lowermost position the vise jaw members 6 and 7 are in 100 their open position, movement upwardly of the piston 28 closing the members 6 and 7 tightly about the drill steel.

Within the cylinder 4 mounted at the rear end of body member 2 a piston 36 operates, 105 carrying therewith a piston rod 37 at the forward end of which is secured a pin 5 by any suitable means as shown at 38. The

piston rod 37 passes through a suitable stuffing box 4^a provided on the rear face of the body member 2. Fluid pressure is admitted to the cylinder 4 at its forward and rear ends by means of ports 40 and 41 opened and closed by movement of the valve 32 operating within valve casing 46. A pipe 45 connected with the rear end of the valve casing 46 in which the valve 32 operates, 5 extends to a point shown at 47 near the forward and heated end of the pin 5 when the pin is in its rearmost position as shown in Fig. 2. Fluid pressure is admitted from the valve chamber 46 in one position of valve 32 10 to point 47 and is emitted through an orifice 48 thus coming directly in contact with the pin 5 for the purpose of maintaining the pin 5 at a low temperature and preventing it from becoming heated to an unsafe degree. This has the effect of rapidly cooling the pin 5 which may have become greatly heated in being thrust forwardly into the drill steel, which when being pinned out is 15 at a red heat. 20 The valve 32 as shown is made up of two spaced heads one at its rear end shown at 32^a and another 32^b separated from the first head 32^a by a reduced neck portion 32^c as shown in Figs. 3 to 8. It is obvious however that this valve may be of any suitable form. 25

Referring now to Figs. 3 to 8 the valve chamber 46 is shown diagrammatically in which operates valve 32. The supply of motive fluid for the various parts of the pinning out machine is shown at 50, this may be of any form, the one shown comprising a conduit 50 in connection with the valve chamber 46 through ports or openings 60. 30 For convenience in Figs. 3 to 8 the ports 60 are not shown. It will be seen that with the valve in the position shown in Fig. 3 a supply to any part of the mechanism is cut off. 40

45 The first movement of the valve 32 is rearwardly or to the right as shown in Figs. 3 to 8 to the position shown in Fig. 4. This opens supply port 50 and admits motive fluid to ports 40 and 30, thus holding the 50 pin in its rearmost position, and forcing piston 28 downwardly to open the jaw members 6 and 7 of vise 3. A continued rearward movement of valve 32 admits motive fluid to the port and pipe 31 which has the effect 55 of raising the piston 28 within cylinder 29 and closing the jaw members 6 and 7 very firmly about the drill steel. This position of the valve is shown in Fig. 5.

The extreme rearward position of the 60 valve 32 is shown in Fig. 6 in which position port 41 is opened admitting pressure to the rear of piston 36 and pushing the pin forwardly into the drill steel inserted in the vise 3. In this position also the port 40 as 65 well as port 30 are opened to the exhaust

through the forward end 61 of the valve chamber 46 so that the pressure is released from the forward and upper ends of cylinders 4 and 29. A forward movement of valve 32 from the position shown in Fig. 6 70 opens communication between the port 41 and the rear end of the valve chamber 46 as shown in Fig. 7, permitting pressure in rear of piston 36 to be exhausted through pipe or conduit 45 and simultaneously opens 75 communication between the supply port 50 and port 40 thus pulling the pin 5 rearwardly. The position of valve 32 shown in Fig. 8 permits fluid to pass into port 30 thus 80 vise 3, the cycle of operation of the machine being completed by a further forward movement of valve 32 in which the valve is in the position shown in Fig. 3.

In order to conveniently operate the valve 85 32 the valve stem 63 is coupled to a reach arm 64 by means of any suitable coupling shown at 65, the reach arm 64 extending forwardly through the body member 2. At the forward end of the arm 64 a coupling 66 is 90 provided, connecting the arm 64 with a handle lever 67 through link 68 and having a handle 69 extending upwardly conveniently located to be grasped by the workman. If desired two handles 69 may be provided 95 symmetrically disposed on either side of the center of the machine. The valve 32 is held firmly in its closed position by means of spring 70 pressing against the coupling 66.

It is understood that the present showing 100 and description disclose only one specific embodiment of my present invention, and that other forms and modifications are included within the spirit and scope thereof, as expressed in the appended claims: 105

What I claim is:

1. In a pinning out machine for drill steels, in combination, a vise having a plurality of movable centering jaws opened and closed by means of fluid pressure, a reciprocable pin mounted to move forwardly and backwardly in relation to said jaw members, fluid operated means for pushing said reciprocable pin forwardly and pulling said pin rearwardly and controlling means comprising a single valve for causing the jaws to close and clamp the drill steel with its axis in alignment with the axis of the pin before the pin is pushed into the drill steel. 110 115

2. In a machine for forcing a pin into and out of a drill steel, the combination of a vise having jaw members, toggle levers operating the jaw members of said vise, a pin movable in alignment with the axis of said jaw members, and means including a valve 120 and cylinders and pistons operatively connected to first actuate the toggle members and close the jaw members and then push the pin forwardly, reversing the movement of said valve causing reversal of the pistons 125 130

and first pulling the pin out of the drill steel and then opening the jaw members of said vise.

3. In a pinning out machine for drill steels, a reciprocable pin, means to push said pin into a heated drill steel and pull said pin out of the drill steel, a conduit extend-

ing from the pin operating means to the forward end of said pin, and means to force motive fluid from said pin operating means through said conduit to cool said pin.

In testimony whereof, I have hereunto set my hand.

RUSSELL H. WILHELM.
